UNITED STATES PATENT OFFICE.

OTTO DIECKMANN, OF CINCINNATI, OHIO.

METHOD OF REFINING PETROLEUM OILS.

Application filed September 1, 1921. Serial No. 497,645.

My invention relates to improvement in method of refining petroleum oils. One of its objects is to avoid breaking down or destroying hydrocarbons, as for instance oils and resinous compounds contained originally in the crude oil, by subjecting them to temperatures at which they decompose. Another object is to separate or remove certain asphalt paraffin and oil compounds and mineral salts and substances before subjecting the crude oil to heat for fractional separation of the illuminating or fuel and lubricating oils by distillation. Another object is to produce illuminating and fuel oils and lubricating oils free from products resulting from the destructive distillation of other substances and compounds. Another object is to recover lubricating oils of higher flash point than customarily produced heretofore. Another object is to increase the percentage yield of lubricating oils. Another object is to separate the asphalt and paraffin substances in the form of cokeless hard pitch as one of the end products. Another object is to simplify the method of refining, and to reduce the amount of loss or waste incident to refining. My invention also comprises certain novel steps and order of procedure, all of which will be fully set forth in the description of the accompanying drawings in which:

Fig. 1 represents diagrammatically an apparatus and order of procedure adapted to the practice of my improved method.

Fig. 2, is a central vertical section through one of the containers illustrated in Fig. 1.

Fig. 3, is a view similar to Fig. 2, illustrating one of the containers of Fig. 1 with the agitating apparatus removed.

In the accompanying drawings a series of tanks or fluid containers are provided and preferably arranged so that the liquids may flow by gravity from one container to another, as may be required. Where the transfer from one container to another can not be conveniently attained by gravity, pumps, pneumatic, mechanical, or other conveyors may be employed to transfer the substances from one container to another.

In Figs. 2 and 3 I have illustrated the general character of container repeatedly employed in my improved method to wash the stock with acid, alkali, and extracting mediums, and warm or heat and agitate the liquids, and when the liquids separate into two or more layers to separately draw off the respective bodies of liquid into different chan-

nels. As illustrated in Figs. 2, and 3, the several containers are preferably lead lined and each comprise a cylindrical portion 60 having a conical bottom 61, a removable lid 62, or if desired a permanent lid with a man-hole therein. A vertical shaft 63 is provided with agitator blades 64, and also preferably a conduit 65 to supply compressed air to agitate the contents of the container. A stock supply conduit 66, a steam pipe 67 near the upper end of the container and a steam pipe 68 near the bottom of the container are provided, said steam pipes being each connected up and adapted to serve as a live steam supply pipe or as a steam escape pipe, the steam being employed to warm or heat and also to agitate the contents of the container and also to assist in flushing and cleaning the containers. At the bottom the containers are supplied preferably with three way valves 69 adapted to be adjusted to conduct a lower layer of liquid from the container, or to successively conduct two or more layers of liquid from the container along the conduits 69' and 69'' to different destinations. A valve controlled offtake conduit 70 is also preferably provided near the lower end of the container to enable one or more upper layers of liquid to be withdrawn leaving the lower layer in the container undisturbed. As illustrated the agitator shaft 63, blades 64 and lid 62 and journal spider 71 are adapted to be lifted from one container and applied to agitate the contents of another container, but may be permanently located if desired.

The crude oil as it comes from the wells varies somewhat in composition, and contains certain asphaltum, paraffin and mineral salts and substances and resinous compounds and oils which are not classified under the regular group or chain of hydrocarbon oils, and some of which when subjected to the higher degrees of heat heretofore usually employed in the fractional distillation of petroleum oils are destroyed or broken down into other compounds or substances, some of which are driven over with and serve to dilute the true hydrocarbon oils or to contaminate them while other portions escape as gases or remain in the residue as a needless waste product. One of the objects attained by my improved method is to separate certain of these compounds and substances from the medium or illuminating and lubricating oils before the medium and lubricating oils are fractionally distilled or subjected to a suffi-

ciently high temperature to result in a de-
structive distillation of any of said com-
pounds and substances.

In the drawings 15 represents one or more
5 containers in which the crude oil to be treat-
ed is stored. From the storage reservoir 15
crude petroleum oil is periodically conducted
to a container 16 by means of a valve con-
trolled conduit 17. In the container 16 the
10 crude oil is treated to remove the small per-
centage of water usually carried by crude oils.
The removal of the water may be effected by
the addition of substances having a strong af-
finity for water, or by other means. The
15 crude oil free from water is then periodically
conducted by means of a valve controlled con-
duit 18 to a container 19, which serves as a
still, to which a mild degree of heat is applied,
sufficient to drive off the more volatile sub-
20 stances such as benzine and gasoline which
are condensed and conducted by means of a
valve controlled conduit 20 to a storage res-
ervoir 21 from which they may be marketed
or further fractionally separated and then
25 marketed.

The crude oil free from the water and more
volatile products is then conducted by means
of a valve controlled conduit 22 to a con-
tainer 24, preferably substantially as shown
30 in Figs. 2 and 3. In the container 24 the
crude oil is mixed with a quantity of sulphuric
acid in concentrated condition from the stor-
age reservoir 23, slowly added, and the oil
and acid thoroughly mixed and agitated for
35 about twenty minutes, whereby an emulsion
of acid, dissolved resins, and other organic
compounds, and mineral salts, asphaltum,
and paraffin compounds is formed as a lower
40 layer in container 24 while an upper layer
contains chiefly the hydrocarbon oils largely
freed from asphaltum, paraffin, mineral com-
pounds, and other substances carried into the
acid sludge or emulsion.

The acid emulsion or sludge is conveyed
45 from container 24 to container 30 by means of
a valve controlled conduit 29, and the acidulated
oils or supernatant fluid from container
24 is conducted by valve controlled conduit
32 to a container 33.

50 The acid sludge emulsion in container 30
is agitated and subjected to live steam until
it reaches a temperature of approximately
70 degrees C. The agitation is then stopped
55 and the steam cut off entirely or cut down to
a small amount about sufficient to maintain
the temperature uniform, whereupon the
emulsion separates into two layers, a lower
one acid sludge containing mineral salts,
60 asphaltum, paraffin, resinous, and other or-
ganic compounds, and an upper layer con-
sisting chiefly of acidulated oil. While still
warm the acidulated oil from container 30
is run into a settling reservoir 25, where the
65 small residue of acid sludge separates out
at the bottom, and the acidulated oil goes

on preferably to the container 33 where it
mixes with the acidulated oil from the con-
tainer 24. The acid sludge slowly accumu-
lating in the lower portion of container 25
is withdrawn from time to time and returned 70
to container 30.

The acid sludge remaining in container 30
is not allowed to cool and has added thereto
from a storage reservoir 26 through valve
controlled conduit 27 a quantity of warm re-
fined petroleum oil, illuminating oil for in-
stance, and the refined petroleum and acid
sludge agitated for approximately twenty
minutes. The agitator is stopped and the
mixture allowed to stand quiescent for about 80
an hour with only sufficient steam to main-
tain a substantially uniform temperature,
whereupon a lower layer of acid sludge is
formed containing the mineral salts, the bulk
of the asphaltum and paraffin compounds,
and other organic substances, and a super-
natant layer containing the extracting me-
dium (refined petroleum) together with such
extractable oils, resins, and substances as
have been extracted from the acid sludge into
the refined petroleum. This last step would
be to a certain extent a reversal of a previ-
ous step, in that it seeks to recover into the
acidulated oil substances previously sepa-
rated therefrom into the acid sludge. The
refined petroleum and extracted matter from
container 30 are preferably conveyed to the
container 33 and mixed with the acidulated
oils therein for further treatment. The ex-
tracting operation in container 30 is repeated,
for instance three or four times, and then
the acid sludge from container 30 is conveyed
to a container 36 for further treatment. If
desired the oils and substances recovered and
extracted from the acid sludge in container
30 instead of being mixed with the contents
of container 33 may be treated and refined
separately from the contents of container
33, and in a parallel line of containers and
substantially as hereinafter described for
the refinement of the acidulated oils in con-
tainer 33.

The acid sludge in container 36 which has
been repeatedly extracted with refined petro-
leum in container 30 has added thereto an
amount of tar oil or crude benzene which is
employed as an extracting medium to extract
the remaining substances of value from the
acid sludge, after the tar oils and acid sludge
have been agitated together at a temperature
of approximately 90 degrees C. and with an
addition of water to about one third of the
volume for about ten minutes, the agitation
is stopped and the contents of container al-
lower to stand quiescent for about an hour
120 to separate into two layers. The lower layer
of extracted acid sludge is run to waste
through a valve controlled conduit 36' or used
for fertilizers and the supernatant liquid
comprising the tar oils and extracted mat-
130

- ter is conducted forward through conduit 36" to a container 37, where it is warmed slightly and while being agitated is neutralized with sodium hydroxide of specific gravity of about 1.10 for instance, to show an alkaline reaction, and the agitation continued for five minutes. Sufficient heat is supplied to maintain the temperature and the contents of container 37 allowed to stand quiescent for about one to two hours to separate into two layers. The lower layer free from oils is run to waste, while the upper layer is refined to yield a hard pitch free from coke stored in container 37" and a cylinder oil of high flash point, stored in container 37" while the tar oils are recovered for future use as an extracting medium.
- The acidulated oils and extracts conveyed from time to time to container 33 from containers 24, 25 and 30 are subjected to agitation and have added thereto in a slow stream a quantity of concentrated sulphuric acid from the reservoir 23 through a valve controlled conduit 23'. Agitation is continued from 15 to 20 minutes, sufficient steam is admitted to maintain the temperature, and the contents of container allowed to stand quiescent for about an hour until it has separated into two layers, acid sludge which is run off and added to the acid sludge of container 30, and acidulated oil. The above operation of washing the acidulated oils in container 33 is repeated two or three times, adding the acid sludge each time to the acid sludge in container 30, after which the washed acidulated oil is allowed to stand quiescent for about two hours and then run off from container 33 into a settling reservoir or container 39. The oil entering the settling reservoir 39 is green in color and substantially free from asphaltum, and is allowed to stand quiescent in container 39 to allow resinous substances and possibly other substances held in suspension to settle out.
- The acidulated oil is conducted forward from container 39 to a container 40 where live steam is admitted to raise its temperature to approximately 80 to 90 degrees C. and the contents of container 40 agitated. A 4% solution of carbonate of soda, about 10 to 15% by weight of the oil is added in container 40 from reservoir 41 and agitation continued for about fifteen minutes. The contents of container 40 is then allowed to stand quiescent for about an hour to separate into different layers. A layer of soda lye of alkaline reaction and brown color is then drawn off to a storage reservoir 41' and may be used with a new addition of soda as a neutralizing material.
- The neutralized oils remaining in container 40 are then agitated and washed with from 20 to 25% by weight of warm water for about five minutes after which the contents of container 40 separates into three layers, a lower watery solution which is run off to waste, a second yellowish brown emulsion, which is run off to a storage reservoir 42, and a layer of neutralized greenish colored oil which is run off to a storage reservoir 43.
- The emulsion in the container 42 is heated by means of a live steam coil 42' which causes it to further separate into an upper layer of greenish oil which is added to the greenish oil in container 43, and a raw soap or soap stock which is conveyed to a reservoir 44 for sale or use in soap making or in the generation of illuminating and fuel gas.
- The greenish oils accumulated in the storage reservoir 43 are conveyed forward to a container or still 45 where they are fractionally distilled. As illustrated they are separated roughly into two fractions one of which is conveyed to a storage reservoir 46 and contains the medium oils, that is all those white and light colored oils such as kerosene, and suited for illuminating purposes, which may be marketed directly from container 46, or may be further fractionated as may be desired. The other fraction of oil from container 45 is conducted to a container 47, and comprises all those heavier hydrocarbon oils usually employed for lubricating purposes. The oils from container 47 would ordinarily be further fractionated and refined. If desired the still 45 may be employed to divide the oils from container 43 into a relatively large number of fractions which would be directly conducted to a much larger number of storage reservoirs taking the place of the storage reservoirs 46 and 47.
- The method herein disclosed is capable of considerable modification without departing from the spirit of my invention.
- What I claim is:
1. The method of refining petroleum oils, which comprises topping the crude oil to separate therefrom fractions liable to produce explosive compounds at normal atmospheric temperatures, washing the remaining heavier oils and asphaltum compounds with concentrated sulphuric acid, separating from the acidulated oil an acid sludge, washing the acid sludge with refined petroleum oil to recover therefrom by solution the acidulated oil carried into the acid sludge, returning the petroleum washing medium and recovered acidulated oil to the main body of acidulated oil, neutralizing the acidulated oil, and subsequently fractionating said neutralized oil.
  2. The method of refining petroleum oils, which comprises distilling off the light and readily volatile oils, washing the remaining heavier oils and asphaltum compounds with concentrated sulphuric acid to separate from the acidulated oil an acid sludge, separating the acidulated oil from the acid sludge, extracting the acid sludge with a refined hydrocarbon liquid solvent, adding said liquid sol-

vent with the substances extracted thereby from the acid sludge to the main body of acidulated oil, neutralizing said main body of oil, and subsequently fractionating said main body of oil.

3. The method of refining petroleum oils, which comprises distilling off the light and readily volatile oils at a low temperature, washing the remainder containing the medium and heavy oils and asphaltum compounds with concentrated sulphuric acid, separating the acid sludge from the main body of acidulated oils, heating the acid sludge moderately, repeatedly washing the heated acid sludge with successive volumes of refined petroleum to recover therefrom by solution the acidulated oil carried into the acid sludge, adding said repeated washing materials to the main body of acidulated oil, neutralizing the main body of acidulated oil, separating a soap stock from the neutralized main body of oil and fractionating the main body of oil after separating the soap stock therefrom.

25 4. The method of refining petroleum oils, which comprises distilling off the light and

readily volatile oils at a low temperature, washing the remainder containing the medium and heavy oils and asphaltum compounds with concentrated sulphuric acid, separating the acid sludge from the main body of acidulated oils, repeatedly extracting the acid sludge with refined petroleum oil to recover therefrom practically all of the acidulated oil, returning the oil recovered from the acid sludge to the main body of acidulated oil, repeatedly washing the main body of acidulated oil with sulphuric acid to separate therefrom additional quantities of acid sludge, adding the acid sludge subsequently separated from the main body of acidulated oil to the original body of acid sludge, neutralizing the main body of acidulated oil, after separation of the acid sludge therefrom, separating a soap stock from the main body of neutralized oil, and fractionating the neutralized oil after separation of soap stock therefrom.

In testimony whereof I have affixed my signature.

OTTO DIECKMANN.
